[57] CLAIM

The ornamental design for a storage container, as shown and described.

DESCRIPTION

FIG. 1 is a perspective view of a storage container showing my new design;

FIG. 2 is a front elevational view thereof;

FIG. 3 is a right side elevational view, the left side being a mirror image thereof;

FIG. 4 is a top plan view thereof;

FIG. 5 is a rear elevational view thereof;

FIG. 6 is a perspective view of a second embodiment of that shown in FIG. 1;

FIG. 7 is a front elevational view of that shown in FIG. 6;

FIG. 8 is a right side elevational view of that shown in FIG. 6, the left side being a mirror image thereof;

FIG. 9 is a top plan view of that shown in FIG. 6;

FIG. 10 is a perspective view of a third embodiment of that shown in FIG. 1;

FIG. 11 is a front elevational view of that shown in FIG. 10;

FIG. 12 is a right side elevational view of that shown in FIG. 10, the left side being a mirror image thereof; and

FIG. 13 is a top plan view of that shown in FIG. 10. The rear of the second and third embodiment is the same in appearance as that of the first embodiment shown in FIG. 5.
